INSOLE

Frank S. Mees, Lynn, Mass.

Application June 11, 1935, Serial No. 25,978

5 Claims. (Cl. 36—43)

This invention relates to insoles for use in women's shoes and consists in an improved method of producing an insole of extreme flexibility having the property of remaining flat under the 5 foot of the wearer in wear even though it may be subjected to extreme and repeated flexing for long periods.

Various expedients have been attempted with 10 a view to increasing the inherent quality of flexibility of the insole in order to make the shoe more comfortable and easier upon the foot of the wearer but in many cases the resulting insole has lost its capacity to remain flat and permits the formation of transverse ridges or wrinkles which 15 become extremely uncomfortable to the wearer. The method of my invention solves this problem and by it an insole may be produced which is of great flexibility, lightness and which remains flat beneath the foot of the wearer under all conditions. Moreover, the method of my invention is 20 entirely practical from the standpoint of modern shoemaking practice and may be carried out economically, rapidly and without requiring special skill on the part of the operator.

25 My invention is characterized by two or more cooperative steps which may be carried out upon the sole while the latter is maintained in the same position and, if desired, as simultaneous operations. It is proposed in the first place to provide one surface of the sole with a band or zone of 30 parallel grooves or corrugations and to form a central cut-out within this band or zone for the reception of a fibrous insert. As a further and optional step it is proposed to perforate the fore-part of the sole by a multiplicity of holes distributed over a defined area therein, which area 35 includes at least in part the grooved or corrugated band. Thus the grooves or corrugations have the effect of rendering the insole flexible, while the removal of the material for the cut-out eliminates the possibility of forming ridges or wrinkles in that part of the sole where they would 40 otherwise be most likely to form, and finally the perforations tend to increase the flexibility of the insole, to lighten it, and also to prevent formation of ridges or wrinkles.

The novel insole herein shown as produced by 45 the practice of my improved method is included within the scope of my invention.

50 As one suitable apparatus for carrying out the method of my invention I have illustrated a press equipped with a die so constructed and arranged that it may be used for carrying out the three characteristic operations above discussed, al- 55 though it will be understood that my invention is not limited to this or to any other type of specific apparatus. I have shown the press, however, as equipped with a paper backing strip and I believe that never before has the operation of cor- 60 rugating or grooving an insole been performed

while the insole is backed up by a paper strip or that perforating and corrugating operations have been heretofore performed simultaneously upon an insole or performed while the insole is maintained in the same position. I am, therefore, defining my invention in method terms with the understanding that any suitable apparatus may be used for carrying it out which is capable of performing the steps defined in the manner stated.

10 The invention will be best understood and appreciated from the following description of illustrative apparatus and of soles of a preferred type, selected for purposes of illustration only and shown in the accompanying drawing, in which

Fig. 1 is a view in perspective of portions of a press showing a sole in operative position therein;

Fig. 2 is a view in perspective of a portion of an insole before treatment;

Fig. 3 is a similar view of a portion of a sole 20 after treatment; and

Fig. 4 is a sectional view showing the position of the insole in a shoe.

In the accompanying drawing I have shown the 25 insole of my invention as it may be constructed of leather or composition material and of a type adapted particularly for use in the "Compo" or any sewed type of shoe, although the invention is not limited to any specific material or in its 30 application to any particular type of shoe.

The insole 24 is shown in Fig. 3 as provided on its lower or outer face with a series of transverse parallel grooves or corrugations 25 arranged with uniform spacing in a zone which includes the ball portion of the sole. The grooves 25 may be of any desired depth and may be formed by pressure or by cutting according as to which method is best adapted to the material employed in the insole. As herein shown the grooves are somewhat more than half the thickness of the insole in depth and their general effect is to render the insole extremely flexible for bending in either direction throughout the zone which they occupy.

The insole is also provided with a series of perforations 26 and these perforations are shown as located within the zone of the grooves 25, uniformly spaced from each other and arranged in a centrally located group between the two margins of the insole. The purpose of these perforations is to lighten the insole, to increase its 45 flexibility and to improve the ventilating and cushioning characteristics of the shoe in which the insole is used. While the perforations 26, as herein shown are located entirely within the zone of the grooves 25, this is a matter of design and the perforations may be located in the insole wherever they are most effective.

In addition to the perforations 26, the insole is provided with a large central cut-out 27, herein

shown as being of circular outline and located midway between the edges of the insole. The cut-out 27, not only lightens the insole but has been found particularly effective in preventing the formation of ridges and wrinkles under wear. It also serves to retain a felt insert 28, which is a part of the complete insole. While I prefer to make this cut-out circular in outline, a cut-out of any curved contour would be within the scope 10 of the invention.

The operations of forming the grooves 25, the perforations 26 and the cut-out 27 may of course, be performed successively upon the insole, but I contemplate a novel method in which they are performed while the sole is maintained in the same position. One form of apparatus satisfactory for this work is shown in Fig. 1 of the accompanying drawing. It comprises a press including a stationary head 10, having a flat pressure face and a movable bed plate 11, carrying the die mechanism. A die plate 12 is bolted upon the bed plate and provided with a pair of similar die blocks 13 in each of which is formed a series 20 of parallel ribs or blades 14. These extend transversely of the press and are closely arranged with uniform spacing. Scattered throughout the die block is a series of tubular punches 15 which are arranged in staggered relation in a centrally disposed group with their cutting edges located in 25 a plane slightly above the plane of the ribs 14. Each of the punch tubes 15 is complete in its periphery and some of the tubes are located in alignment with ribs 14, while others are spaced between adjacent ribs, that is to say, the location of the punch tubes with reference to the ribs is such that in the finished sole some of the 30 perforations 26, are intersected by the grooves 25, while others are located substantially between adjacent grooves. Each die block is also provided with a circular cut-out die 16, which is centrally located and arranged with its cutting edge in substantially the same plane as the cutting 35 edges of the punch tubes 15.

The movable bed plate is provided also with a gauge and stripper plate 18, having apertures to 40 clear the die blocks 14, and being yieldingly mounted to support the previously formed insole blank normally in a plane above the die block. The plate 18 is provided with side gauge pins 19 which are adjustable to accommodate soles of 45 different widths, and with adjustable heel gauges, 20, which determine the longitudinal position of the soles with respect to the die blocks and so bring the selected area of the forepart above the 50 die block 13.

The press is provided with mechanism for feeding a paper strip 22, intermittently across the pressure face of the head 10. The paper backing thus provided not only insures clean cutting 55 of the punch tubes 15, and the cut-out die 16, but cooperates with the ribs 14 to prevent damage to the insole stock during the operation of impressing the corrugations or grooves into the insole. It is believed that never before has a 60 paper backing been provided for carrying out simultaneously perforating and indenting operations upon the sole. The mechanism for advancing the paper strip 22, is not herein shown since it forms no part of the invention, but it 65 will be understood that between operative movements of the bed plate the strip is advanced sufficiently to present a fresh surface in line with the individual punch tubes. It will be apparent 70 that the insoles may be presented in pairs to the 75 press and that a right and left insole are simul-

taneously operated upon, although when insoles of composition material are dealt with a right or left design may be secured simply by reversing the insole upon the plate 18.

Upon removal from the press the insole is made ready for use by the placing in the cut-out 27, a circular insert 28, of felt or other flexible fibrous material. Ordinarily this will require no securing means, but will be slightly compressed laterally and thus held in place by the walls of the 10 cut-out 27. I prefer to use felt in this location since it is light, absorbent and non-wrinkling and provides a cushion beneath the foot of the wearer which supplements to some extent the cushion effect of the perforations 26 in the insole. 15

In Fig. 4, the complete insole 24 is shown as incorporated in a shoe 30 having an outsole 31, and it will be apparent that the grooves 25 are thus located in the most effective position in the shoe to facilitate the flexing under the foot of 20 the wearer, while the other features described tend to prevent the gradual building up of transverse ridges during repeated flexing. In the finished shoes the insole 24 is covered by a sock 25 lining 29 and the felt insert 28 is held in place beneath this lining where it allows circulation of air between the outer and inner soles with a pronounced cooling effect while the shoe is being worn.

As already noted the three operations of grooving, perforating and forming the cut-out 27 are performed while the sole is retained in the same position, but the method of my invention goes further than that and provides a procedure whereby these three operations may be simultaneously performed, thus insuring accuracy in the product and great economy of time. 35

Having thus described my invention what I claim as new and desire to secure by Letters Patent of the United States is:—

1. An improved insole having in the ball portion of its outer face a series of parallel transverse grooves intersecting a relatively large cut-out and a plurality of perforations distributed about the borders of said cut-out, and a felt insert 45 in said cut-out.

2. An improved flexible insole which will flex without wrinkling, having a band of parallel transverse grooves impressed in the ball portion of its outer face and a relatively large, centrally disposed circular cut-out which is intersected by the intermediate grooves of said band and not by the marginal grooves thereof. 50

3. An improved insole adapted to flex in use without wrinkling, having a band of transverse 55 grooves formed in the ball portion of one face and a relatively large symmetrically shaped cut-out which is intersected by some of said transverse grooves and contains an insert of felt-like material. 60

4. An improved insole adapted to flex in use without wrinkling, having a wide band of close-set transverse grooves impressed in one face and a circular cut-out located substantially centrally both in said band and width-wise in said sole. 65 and a felt-like insert contained in said cut-out.

5. An improved ventilated insole having a well defined band of close-set transverse depressions in one face, a cut-out of substantial size so located as to interrupt some of said depressions and containing a felt-like insert, and a group of smaller perforations in the insole surrounding said cut-out. 70
